COMBINATION BUMPER AND TRAILER HITCH

Ted L. Cline, P.O. Box 38, Rush Springs, Okla.

Filed Apr. 12, 1963, Ser. No. 74,403

Term of patent 14 years

(Cl. D14—6)

I claim:

The ornamental design for a combination bumper and trailer hitch, as shown.
